COMPARTMENTED SERVING TRAY

Glenn David Boyd, Cherry Hill, N.J., assignor to Campbell Soup Company, Camden, N.J., a corporation of New Jersey

Filed June 17, 1965, Ser. No. 85,788

Term of patent 14 years

(Cl. D44—10)

FIG.1.

FIG. 2.

FIG.3.

FIG.4.

FIG.5.

FIG.6.

FIG. 1 is a perspective view of the compartmented serving tray;

FIG. 2 is a perspective view thereof with the lid removed from the soup compartment;

FIG. 3 is a top plan view thereof;

FIG. 4 is a front elevational view thereof;

FIG. 5 is an end elevational view thereof; and

FIG. 6 is a sectional view thereof taken on line 6-6, FIG. 3.

I claim:

The ornamental design for a compartmented serving tray substantially as shown.
